UNITED STATES PATENT OFFICE

2,008,913

SHEDDING MECHANISM FOR CIRCULAR LOOMS

Joanny Jabouley, Spondon, near Derby, England,
assignor to Celanese Corporation of America,
a corporation of Delaware

Application January 12, 1934, Serial No. 706,320
In Great Britain January 24, 1933

3 Claims. (Cl. 139—16)

This invention relates to shedding mechanism for circular looms, and in particular is concerned with the method of shedding in which a warp thread is deflected out of its normal line at one point in its length and controlled at another point to determine whether this deflection shall be effective to permit the thread to be moved to one side of the shuttle, or ineffective to retain the thread on the other side of the shuttle.

Such further means may comprise a reed through the dents of which some of the warp threads pass while the other warp threads pass through holes in the dents. Thus, for example, for plain weaving every alternate thread is free to move between reed dents, while the remaining threads are controlled by the holes in the dents, so that on sideways pressure the threads passing between pairs of dents are deflected to one side, while those passing through the holes are retained, the threads thus being divided into two sheets between which the weft inserting means can pass.

According to the present invention the deflection of the threads is effected by means of rotatable wheels whose edges are covered with fabric, felt, or the like so that when the warp threads are engaged by the wheels projecting beyond the normal line of the warps, they are carried evenly round the periphery of the wheels, the covering resisting the tendency of the threads to slip along the edges of the wheels. The fabric or like covering thus avoids damage to the threads, a feature which is particularly important in the case of relatively weak warp material, and especially of continuous filament threads where there is a danger of individual filaments being broken.

The edges of the wheels are preferably broad so as to engage a substantial length of the threads, and also curved, so that the warps are not sharply bent at the wheels on deflection, but pass smoothly from the warp supply to the fabric.

The invention will now be described in greater detail with reference to the accompanying drawing in which

Fig. 1 is a vertical section showing the shedding wheel in operation;

Fig. 2 is a diagrammatic plan view of part of a circular loom showing the shedding wheels in connection with two consecutive shuttles;

Fig. 3 is a part sectional view of the shedding wheel to a larger scale; and

Figs. 4, 5 and 6 are further vertical sections showing the shedding wheels in operation.

Figs. 1, 4, 5 and 6 correspond to views taken

on the lines 1—1, 4—4, 5—5 and 6—6 of the diagrammatic Fig. 2.

Referring to Fig. 1, the warp threads 7 are shown proceeding downwardly from a warp supply (not shown) through spacing means 8 to a reed 9 whose dents are provided with eyes 10, alternate threads being passed through said eyes and the remaining threads between the dents. Below the reed 9 the warps proceed downwardly to the level of a ring 11, fabric 12 formed by the insertion of weft between the reed 9 and the ring 11 passing over the face of the ring down to take-up means (not shown). By the reason of the threading of the warp threads alternately between the dents of the reed 9 and through the eyes 10 in the dents, every other thread is constrained by the reed to follow a substantially direct path from the eye 10 to the ring 11.

The shuttles 13 are disposed in sequence round the loom, as shown in Fig. 2, and in advance of each shuttle there is disposed a shedding wheel 14 pivotally mounted on a suitable support 15. The shedding wheels, which are preferably made of wood or other like material, are of considerable depth and smoothly curved at their periphery, as is clearly seen by reference to Fig. 3. The periphery, moreover, is covered with a layer of soft fabric 16.

The supports 15 for the shedding wheels 14 are so disposed as to project the periphery of each wheel beyond the line 17 followed by the warps in proceeding directly from the spacing means 8 to the reed 9. At alternate shuttles the wheels 14 project into the warps from opposite sides of the warp circle, as is shown in Fig. 2. Because of the pushing of the warps 7 above the reed 9 out of the circle 17, the alternate warps 18, which pass between the dents of the reed, follow a direct line from the periphery of the wheels 14 to the upper edge of the ring 12, whereas the alternate warps 19, which are constrained by the eyes 10, must retain their original direct path from the reed 9 to the ring 11. The alternate warps thus form two sheets, as is clearly shown in Fig. 1, the spacing between the sheets being sufficient to permit the entry of the nose 18 of the shuttle 13 which, as shown in Fig. 2, is so disposed with respect to the wheel 14 that it encounters the warps while they are held separated by the wheel.

It being understood that there is relative angular movement between the shuttles 13 and the warps 7, for example the shuttles 13 rotating while the warps 7 are held stationary, or the warps rotating while the shuttles are held stationary, as described in U. S. application S. No. 55

655,560 filed 7th February, 1933, the advance of the shuttles 13 relative to the warps results in the shuttle body continuing to push the warps 1x, 1y apart, these passing over the sides of the shuttle 5 until they converge again at the rear end 19 of the shuttle to return to the original circle 17. Fig. 1 shows the alternate warps 1x being pushed outwardly to provide for the entry of a shuttle such as that shown at the right-hand side of Fig. 2, and Fig. 4 shows such shuttle passing between the two sheets of warps. The shuttle is held in vertical position by the vane wheel and roller mechanism shown in Fig. 4, this being similar to that described in U. S. application S. No. 15 706,322 filed on even date herewith, the outer sheet of warps 1x passing between the vanes of the wheel 20 and the inner sheet of warps passing between the roller 21 carried by the shuttle and the race 22 over which the roller 21 rolls. 20 Fig. 5 shows the warps 1 being pressed inwardly above the reed 9 by the shedding wheel 14, as shown at the left-hand side of Fig. 2, the warps 1x then lying below the reed on the inside of the normal warp line 17. In Fig. 6 the shuttle 13 is shown having entered the shed formed as described with reference to Fig. 5, the alternate warps 1y passing to the outside of the shuttle through the vanes of the wheel 20, and the warps 1x passing to the inside of the shuttle between the 25 roller 21 and the race 22.

It will be understood that a similar disposition of shedding wheels and shuttles to that shown in Fig. 2 is followed round the whole loom periphery, the shedding wheels being disposed alternately 35 inside and outside the warp circle at every other shuttle 13 so that as soon as the warps 1x have been pushed to one side of the warps 1y to form a shed for one shuttle, they are then pushed to the other side of the warps 1y to form an opposite site shed for a succeeding shuttle.

The wheels 14 are freely mounted so as to be easily rotated by their engagement with the warps, and the fabric covering 16 of the wheels

14 engages the warps firmly and holds them in evenly spaced relationship while pushing them to one side of their normal line. The covering thus avoids damage to the threads, especially in view of the relatively large length of the threads engaged by the ring (see Fig. 3), this being due to the considerable breadth of the edges of the rings. The smooth curvature of the edges enables the warps to be deflected without sharp bending. 5

The warps may be threaded otherwise than alternately through the eyes 10 and between the dents 9. For example, two or more can be passed through any eye or between any pair of dents in accordance with the pattern desired. 10

The wheels according to the invention may be used with other devices operating to make a selection among the deflected warp threads. For example, the wheels may be used with healds governed by selector mechanism, as described in 20 U. S. application S. No. 706,319 filed on even date herewith, according to which some threads are freed from movement under the force imparted by the deflection, while others are restrained from such movement, the selection of the healds being 25 in accordance with the pattern desired.

What I claim and desire to secure by Letters Patent is:—

1. In circular loom shedding mechanism of the type described, a rotatable warp-engaging shedding wheel, said wheel having its edge covered with material adapted to resist slipping of the threads along the edge. 30

2. In circular loom shedding mechanism of the type described, a rotatable warp-engaging shedding wheel, said wheel having a broad edge to engage a substantial length of the threads and a fabric covering for said edge to resist slipping of the threads along the edge. 35

3. A shedding wheel according to claim 1 40 having a curved edge to avoid sharp bending of the threads.

JOANNY JABOULEY.
